To all whom it may concern:

Be it known that I, August O. Elting, a citizen of the United States, residing at Chicago, in the county of Cook and State of Illinois, have invented a new, original, and ornamental Design for an Arm for Lamp Fixtures, of which the following is a specification, reference being had to the accompanying drawing, forming a part thereof.

Referring to the drawing:

Fig. 1 is a top plan view of an arm for lamp fixtures embodying my new design;

Fig. 2 is a side elevational view of the same;

Fig. 3 is a bottom plan view of the same; and

Fig. 4 is a front elevational view of the same.

I claim:

The ornamental design for an arm for lamp fixtures, as shown.

AUGUST O. ELTING.
